BLANK FEEDING MECHANISM

William W. Criley, Cleveland, Ohio

Application August 20, 1932, Serial No. 629,653

21 Claims. (Cl. 10—12)

This invention relates to a blank feeding mechanism designed to transfer blanks from a feed delivery point or station to a work station and to discharge the same therefrom.

5 A primary object of the invention is to construct a simple, efficient, fully automatic operating device of this character, capable of feeding blanks successively to a plurality of stations such as the work stations, that is, places where the blanks are to be held and work performed upon the same, and then to discharge them from the last station.

The feeding mechanism is designed to grasp oblong blanks or blanks longer than their width, such for example as bolt blanks, and a further object of the invention is to so arrange such a feeding mechanism that it may cooperate in timed relation with a bolt heading machine or the like, and which shall be capable of certainty of operation, and be simple in construction, and a further object is to so design it as to require no changes, or at least a minimum of changes in a modern bolt heading machine of the character, having gripping dies embracing the shank of the blank in two or more positions during roughing and finishing heading operations of heading dies.

15 A more specific object of the invention is to so arrange a mechanism that it may handle or move a plurality of blanks successively, that is, on each movement of the feeding mechanism a fresh blank is taken from the feed delivery point, while the blank or blanks previously acted upon by the dies are advanced one station, that is either from a roughing station or from the finishing station, and dropped or suitably discharged.

20 The embodiment of the invention shown in the accompanying drawings is intended for use with very large heading machines acting on blanks automatically, and in connection with which are afforded many difficult mechanical problems, inasmuch as blanks of several inches in diameter, from a foot to several feet long, are to be fed successively to the operating dies, and must be presented thereto in such fashion as to be accurately positioned in the die. They must be moved in precise timed relation to the reciprocating opening and closing movements of the respective die members. The gripping and carrying means engaging the blanks must be arranged so as not to interfere with the operation or require any special design or impair the function of the dies or other parts of the machine.

25 More specific objects are to so construct the mechanism that it may be capable of being simply manufactured, very durable in use and have

a capacity for handling, with certainty, large, heavy blanks (while being equally well adapted when designed in a smaller size to handle small blanks), and, in short, of a character not only unlikely to get out of order, but to have an operative life corresponding to that of the heading machine itself.

30 A still further object is to arrange to handle the blanks so that they may be moved quickly and yet without jerking motion from station to station, and without in any way interfering with the timing or causing any delays in the operation of the heading, or other, machine with which feeding mechanisms may be combined.

35 A still further specific object is to so arrange a pair of opposed gripping elements capable of grasping a plurality of blanks simultaneously and of advancing them each to the next station, and one of which shall be cooperative with one of the receiving elements or die members, thus holding it in position while permitting the start of, or a portion of, its return movement to pick up the next blank, and while the other of the gripping elements is moved to one side away from and clear of the blanks during this starting or return movement.

40 Another specific object is to provide a simple and efficient arrangement of operating mechanism for vertically moving the gripping arms and for opening and closing them upon the blanks in the relative timed movements, that is, moving one arm away from the blanks ahead of the other, and all from a common actuating means arranged in compact form and adapted to be connected with the driving or one of the moving elements of the header or other machine to which the feeding mechanism is attached.

45 It will be understood that many changes and alterations may be made without departing from the spirit of my invention.

Describing the illustrative embodiment which is for large heading machines in connection with the illustrations of the accompanying drawings:—

50 Fig. 1 is a side elevation of the feeding mechanism mounted in operating position on the bed frame of a horizontal upsetting machine.

55 Fig. 2 is a plan view of the same, with a part of the structure in the upper left of Fig. 1 removed to show more clearly the cam and lever mechanism.

Fig. 3 is a fragmentary semi-sectional view along the line I—I in Fig. 2.

Fig. 4 is a fragmentary plan view along the line II—II in Fig. 3.

Using reference characters for convenience to describe the embodiment of my invention illustrated in the accompanying drawings, the upsetting machine is designated in its entirety at 5 A, and the group of parts of the feeding mechanism comprising the cam and lever group, designated in their entirety at B, are compactly arranged in a supporting housing 10 which has been shown in this case for convenience as mounted on a cover plate 12 of the upsetting machine A. The group of parts comprising the transfer mechanism, designated in their entirety at C, are supported and actuated by the levers 58, 78 and 86 connecting them with the cam and lever group B. The hopper mechanism, designated in its entirety at D, may be suitably mounted on a horizontal face 14 of the upsetting machine A. The cooperative action of the whole mechanism with the upsetting machine is as follows:

Heated metal blanks W are fed into a hopper 16 of the hopper mechanism D at a point 18 and roll down an incline plane 20 where the first of these blanks engages a pair of escapement pins 22 and stops at a position designated W1. With the upsetting machine in operation, the forward and backward movement of the heading ram 26 causes a rocking or oscillating motion of an auxiliary shaft 28, which may be accomplished by any of the well-known methods. As shown, this shaft 28 is connected to a rocker arm 30 through an arm 32, link 34 and arm 36, and its action is so timed that during the backward or withdrawal stroke of the heading ram 26 the auxiliary shaft 35 28 rocks in the direction to cause the rocker arm 30 to force the escapement pins 22 downwardly and the cooperating escapement pins 23 upwardly, and during the forward or upsetting stroke of the ram the auxiliary shaft 28 rocks in the direction to cause the upper pair of pins 22 to be forced upwards and the lower pair of pins 23 downwards. The movement of the escapement pins is such that they clear the blanks in their extreme upward position, and it will therefore be obvious that the blanks are thereby fed, one by one, down the inclined plane 20 to a shelf or shoulder 38 where their motion is arrested and they are supported in a horizontal position. As the blanks fall onto the shelf 38 the heading ram 50 26 has withdrawn to its extreme position. As the ram starts its forward movement, a pusher pin 40, shown, for example, as secured in an extended portion of the ram 26 (see Fig. 3) engages the blank and moves it forward to the position indicated at W2 where one end engages a stop 46.

While the hopper mechanism D is shown in the several views disposed with respect to the transfer mechanism C such that blanks are pushed from left to right, as viewed in Fig. 3, in position to be gripped by the gripping fingers 118 and 132, it is to be understood that this is not the only arrangement which I may use. For example, I may arrange the hopper feeding mechanism D, as shown in Fig. 3, to the right of the transfer mechanism C, so that blanks are pushed from right to left to be in position to be gripped by the gripping fingers 118 and 132. In a like manner I do not wish to be limited to the exact method employed in pushing the blanks from the shelf 38 to the position indicated at W2 but it is to be understood that any suitable means may be employed. For example, instead of having a pusher pin 40 secured in an extended portion 42 of the heading ram 26, I may use any suitable means.

such for example as a set of levers, either actuated by the ram 26 or independently thereof, and this mechanism may be adapted to push the blanks from left to right or from right to left, depending upon the location of the hopper mechanism D with respect to the gripping or transfer mechanism C. It will be understood, of course, that if the blanks are fed from right to left, as viewed in Fig. 3, the topmost portion of the stop 46 would be removed and a suitable stop arranged at the left end of the blank.

In a like manner I do not wish to be limited to the exact arrangement of escapement means shown for releasing the blanks from the hopper mechanism one by one, but I may use any suitable design within the scope of the appended claims. This escapement means need not necessarily be actuated by a rocking shaft such as that indicated at 28 but may be actuated, for example, by a system of levers, a rack and gear, a toggle mechanism, or the like, all of which may be either co-operative with the movement of the heading ram and actuated therefrom, or may be actuated from entirely independent means.

As shown, the blank at W2 is thereafter moved laterally to the left, then downwardly and inwardly to the right by the gripping fingers 118 and 132, where it is presented to the first upsetting die in the position indicated at W3. The finger 118 then recedes further to the right to clear the blank while the finger 132 continues to press it into the cavity of the upsetting die as both fingers rise to complete another transfer cycle. These operations may be accomplished as will now be described.

A shaft 48 of the cam and lever mechanism B is suitably connected to the driving mechanism of the upsetting machine, and disposed on and secured to the shaft are cams illustrated at 50, 51 and 52. As shown, the cam 50 is adapted to cause the transfer mechanism C to be moved upward and downward through the action thereon of a roller 54 secured in the end of a rocking lever 56. This lever 56 is pivotally mounted on a shaft 58, which may be secured in bearings as 60, on the housing 10. The other end of this lever 56 is bifurcated to receive transfer arms 62 and 64 pivoted to the lever 56 as by a pin 66. The arm 64 may be secured to the pin 66 by a set screw 67, while lever 56 and arm 62 are free to swing thereon. The roller 54 in lever 56 may be forced against the cam 50 by action of a spring 68 pressing against a stop 70 and acting through a spring rod 72, pivotally secured in an arm 74 rigid with the lever 56. The other two cam elements 51 and 52 actuate the gripping elements of the transfer mechanism C. As shown, the cam 51 actuates the carrying arm 62 through a roller 76, a rock lever 78, a connecting rod 80, an eye 82 and pin 83 to cause short lateral movements thereof. The cam 52 actuates the carrying arm 64 through a roller 84, a rock lever 86, a connecting rod 88, eye 90 and pin 91, to cause corresponding short lateral movements. The pressure of roller 76 against cam 51 is maintained by action of spring 92 pressing against the stop 94 and acting through spring rod 96 pivotally secured in the extension 98 of the rock lever 78. In a like manner roller 84 is pressed against cam 52 by action of spring 100 pressing against stop 70 and acting through spring rod 102 and arm 104. The rock levers 78 and 86 are pivotally mounted on the shaft 58 and are shown curved downward (see Fig. 1) to avoid interference with a reinforcing member 108 extending longitudinally of the upset-

ting machine. The connecting rods 80 and 88 may be adjustably connected to the eyes 82 and 90, respectively, by having their ends threaded, as at 110, and being screwed into eyes 82 and 90 with locking nuts 112 and 114 to prevent loosening. These eyes in turn are pivotally connected to the transfer arms. A suitable removable cover 106 may enclose the top of the cam mechanism.

Secured to the carrying arm 62 by bolts 116 is a gripper finger 118, preferably tongued and grooved into the arm 62 as at 120, and adjustable therewith by action of bolt 122, the finger 118 being provided with slotted holes 124 for the bolts 116. Notches 126 are provided for the purpose of gripping the blanks to be fed to the upsetting dies, as will be hereinafter described.

Secured to the carrying arm 64 by bolts 128 is an adjustable supporting block 130 for the companion gripping finger 132. This latter may be a spring finger but may be otherwise as will be hereinafter discussed. An adjusting bolt 134 acts in like manner to the bolt 122 as just described in connection with the finger 118.

Assuming that the first heated blank has been delivered to the shelf 38 and pushed against stop 46 to the position W2, as the ram 26 starts to withdraw again to the extreme open position the coupling of the cam shaft 48 with the driving mechanism, and the timing of cams 50, 51 and 52 on the shaft 48, are such that the raising and lowering cam 50 is passing through a dwell period and the gripper finger actuating cams 51 and 52 have just actuated the levers 78 and 86 to cause the fingers 118 and 132 to grip the blank, the transfer mechanism C then being in the position shown in Fig. 1. As the operation continues, the finger spreading and closing cams 51 and 52 actuate the rock levers 78 and 86, respectively, to cause the gripping fingers 118 and 132 to move together in gripping position, then laterally to the left (Fig. 1) just far enough for the blank in position W2 to clear the supporting shelf 38. The housing around the support 38 is cut away at 136 to permit this movement of the blanks (see Fig. 3). Following this first pick up movement dwell periods occur on both gripping action cams 51 and 52, but the raising and lowering cam 50 now actuates lever 56 to cause the transfer mechanism C to move downward in a recessed portion 138 of the stationary gripper or clamping die 140 and a recessed portion 139 of the moving gripper or clamping die 142, which latter die at this juncture has just reached its extreme open position. When the blank held by gripping fingers 118 and 132 reaches the point just opposite the first upsetting stage of the stationary gripper or clamping die 140, the lowering stops by a dwell period occurring on cam 50 and the finger actuating cams 51 and 52 then actuate rock levers 78 and 86 to cause the fingers 118 and 132 to move the blank to the right thereby presenting it to the cavity in the stationary die 140 at position W3.

Thereafter the gripping finger 118 is moved laterally to the right just far enough to clear the blank, by action of the lateral actuating cam 51 acting through rock lever 78. Both gripping fingers 118 and 132 are then raised by action of the raising and lowering cam 50 acting through rock levers 56, while the finger 132 continues to press against the blank due to a dwell period on its actuating cam 52 thereby holding the blank in the cavity of the clamping die 140 by a sliding action over the blank during the upward move-

ment of the transfer mechanism C. This permits a more rapid action of the whole feeding mechanism as it is not necessary for the gripping finger to retain hold of the blank until the gripper dies close. While I have indicated that the fingers 118 and 132 may begin their upward motion before the closing of the gripper or clamping dies 140 and 142, it is to be understood that while this is very advantageous in many cases the invention is not to be limited to this particular operation, but that by suitably designing the finger actuating cams 51 and 52 I may cause these fingers to retain hold of the blank until the gripper or the clamping dies 140 and 142 have closed and may thereafter either release the blank or hold it for any predetermined length of time, as desired. While the transfer mechanism is ascending the gripper dies 140 and 142 close and the heading ram 26 moves in to complete the upsetting operation.

As the transfer mechanism C reaches its extreme upward position a dwell period occurs on raising and lowering cam 50, while finger actuating cam 51 actuates rock lever 78 to cause the gripper finger 118 to move laterally to the left until the finger engages the newly presented blank, indicated again at W2, in its upper notch 126. The transfer mechanism is now in the position shown in Fig. 1 and ready to repeat the sequence of operations just described. While the gripper fingers 118 and 132 are gripping the blank in their extreme upward position the heading ram 26 and the movable die 142 start moving to their extreme open positions.

As the upsetting machine continues to operate it will be quite apparent that by suitably positioning the notches 126 in gripping finger 118 and as the transfer mechanism C moves upwardly and downwardly, that not only is a new blank selected and presented to the gripper dies for the first upsetting operation on each downward movement of the transfer mechanism, but that the blank previously presented to the gripper dies is picked up and presented to other points, as indicated at W4 and W5, in the gripper dies for successive upsetting operations. As the last of these operations is completed and the movable gripper or clamping die 142 moves away from the stationary gripper or clamping die 140, the finished piece, indicated as at W5, is ejected from the die 140 by the extension 146 of gripper finger 118 as it moves to the left prior to the downward movement of transfer mechanism C. This ejection occurs before the movable gripper or clamping die 142 closes, and the finished piece drops clear of the dies.

In Fig. 1 the stop 46 has been removed to more clearly show the gripper fingers 118 and 132 and other positions that the blanks may assume during subsequent upsetting operations. In Fig. 3 the clamping dies 140 and 142 are shown recessed intermediate of their ends to receive the gripper fingers 118 and 132, but it is to be understood that they may be recessed in any other suitable manner as for example, adjacent the right end as viewed in Fig. 3, or the gripper fingers 118 and 132 may be entirely exterior of the clamping dies, as for example to the right of them, either of which may be accomplished by simple modifications of the structure shown.

As heretofore indicated, the gripping finger 132 may be of a spring construction, but I do not wish to be limited to such. For example, I may make finger 132 of heavier material than indicated in the drawings, notch the finger similar

to that shown for finger 118, and attach it to the carrying arm 64 by an intervening spring member, so that it may press against the blank under spring tension during its upward motion. 5 Or further, I may make the finger 132 a duplicate of that of finger 118 and so design the actuating cam 52 so that when the blank is presented to the cavity of the stationary gripper or clamping die 140 the finger 132 is given a short lateral movement to the left, as viewed in Fig. 1, so 10 that as the transfer mechanism C moves upwardly both fingers will clear the blanks. Again, I may interchange fingers 118 and 132, as shown in the drawings, that is, I may make the finger 15 to the right in Fig. 1 of spring construction, or spring actuated, and the finger to the left of rigid structure, in which case the finger actuating cams 51 and 52 may be designed to impart movements to the fingers in any manner 20 so desired. For example, the fingers may be made to retain hold on the blank during the closing of the gripper dies 140 and 142 and for a period of time thereafter during the heading operation, or they may release the blank as soon 25 as the gripper dies have closed.

It will be seen that the action of the transfer mechanism in co-operation with an upsetting die is to cause a substantially rectangular movement of the blanks and the gripping fingers, and that 30 the finger actuating mechanism may be so designed as to either start the return upward motion of the fingers before the gripper or clamping dies close, or cause the fingers to retain hold of the blank until the dies close and then start 35 their upward movement, or retain hold of the blank during a portion of or all of the upsetting operation, as desired. It will also be seen that not only are new blanks presented to the first 40 upsetting dies but that the fingers are adapted to advance previously acted upon blanks to subsequent dies, and to thereafter eject the finished product from one of the dies.

I claim:

1. The combination with a pair of gripper dies 45 adapted to open and close to grip a blank fed thereto, of means for presenting a blank to said dies while open and thereafter to release said blank as said dies close, said means including a pair of fingers having a common arcuately 50 moving pivot, and each of said fingers having associated therewith an independently actuated controlling means to cause independent movement of each finger.

2. The combination with relatively movable 55 dies having a plurality of complementary opposed cooperating recesses therein which constitute die stages, of means for presenting a heated blank to the first of said die stages, said means being also adapted to transfer at the same time 60 previously acted upon blanks in the other die stages to a subsequent die stage and to simultaneously eject the finished blank from the last die stage, said means including a pair of fingers having a common pivot, and controlling mechanism for independently actuating each of said fingers.

3. The combination with relatively movable 70 dies having complementary opposed recesses therein which constitute a die stage, of means including a pair of gripper elements for presenting a blank to said die stage by a combined horizontal and vertical movement of said elements, one of said gripper elements pressing against 75 and holding the blank in the recess in one of said

dies for an interval during a vertical movement of both gripper elements.

4. The combination with relatively movable dies having complementary opposed recesses 5 therein which constitute a die stage, of means including a pair of fingers for presenting a blank to said die stage, one of said fingers pressing against and holding the blank in the recess in one of said dies for a predetermined interval of the return movement of said finger for the 10 next blank.

5. The combination with relatively movable dies having a plurality of complementary opposed recesses 15 therein which constitute die stages, and including a roughing die stage and a finishing die stage, of means including a pair of fingers for presenting blanks to the roughing die stage and at the same time transferring blanks from the roughing die stage to the finishing die stage, said fingers being pivotally joined at one end 20 and independently actuated intermediate both ends, one of said fingers being adapted to eject the blank from the finishing die stage simultaneously with transfer of a blank thereto.

6. The combination with an upsetting machine 25 having a pair of gripper dies with complementary recesses therein, one of said dies being movable and having an open and a closed position, of means including a pair of mutually pivoted, independently controlled fingers for passing between said dies in said recesses when the movable die is in its open position to present a blank therebetween, and thereafter to release said blank when the movable die moves to its closed position, and to eject said blank from said dies 30 when the movable die moves to its open position.

7. The combination with an upsetting die, of a pair of fingers for presenting blanks to said die, said fingers being pivotally secured together at one end, means for actuating said fingers intermediate their ends to grip a blank with their free ends, said means being adapted to cause simultaneous lateral movement of said fingers at one time and independent lateral movement of each finger at other times to cause said fingers to grip 45 a blank and present it to said die and thereafter release it.

8. The combination with an upsetting die of means for receiving heated blanks, means for feeding the blanks from said receiving means 50 one at a time, and moving and separately controlled opening and closing fingers for gripping the blanks and presenting them to the upsetting die and thereafter releasing the blanks during the action of the die.

9. The combination with an upsetting die, of an inclined plane for receiving heated blanks, means for restraining the blanks on said inclined plane and releasing them one by one to roll down the inclined plane, a shelf for arresting the motion of said blanks as they roll from the inclined plane, means for causing a lateral movement of the blanks, and means including a pair of mutually pivoted, independently controlled fingers for gripping the blanks on said shelf and presenting them to the upsetting die, each of said fingers being independently operated, whereby one of said fingers is subsequently caused to eject a blank from said die when both of said fingers are gripping a fresh blank on said shelf.

10. The combination with an upsetting machine having a ram movable in a forward and backward direction, of means for receiving heated blanks, said means having an inclined plane down which said blanks may roll by gravity effect,

5

means for restraining the movement of said blanks on said inclined plane and for releasing one blank during each backward stroke of said ram, and means including a pair of mutually pivoted, independently controlled fingers for gripping the blanks as released and presenting them to the upsetting die by a rectangular movement of said fingers.

11. The combination with a pair of clamping dies, each of said dies having a recess in one face co-extensive with its depth, said dies having an open and closed position, means including a pair of fingers for presenting blanks to said clamping dies while in the open position by a combined 15 horizontal and vertical movement of said fingers into the recessed portion of said dies.

12. The combination with relatively movable dies having complementary opposed recesses therein which constitute a die stage, of a hopper 20 for receiving heated blanks, said hopper being inclined so that the blanks are normally urged toward one end of said hopper by gravity effect, means for restraining the blanks in said hopper and for releasing them one by one, a rigid shelf 25 disposed at one end of said hopper and adapted to receive the blanks as released, means including a stop for moving the blanks endwise along the shelf against the stop, and independently moving blank gripping fingers for lifting the 30 blanks from the shelf laterally and presenting them to the die stage by a combined vertical and horizontal movement, one of said fingers pressing against and holding a blank in the recess in one of said dies during the return vertical movement 35 of said finger.

13. In combination with a die adapted to receive a blank fed thereto, means for presenting a blank to said die, said means comprising a pair of fingers having a common fulcrum, means for actuating each of said fingers independently of the other finger and of movement of the fulcrum to cause said fingers to grip a blank, and means for moving the fulcrum and for moving the fingers relative to the fulcrum whereby a blank 45 held by the fingers may be moved both vertically and horizontally.

14. The combination with relatively movable dies having complementary opposed recesses therein which constitute a die stage adapted to receive a blank fed thereto, means for presenting a blank to said die stage, said means comprising a pair of mutually pivoted fingers, means for actuating said pivot along an arcuate path, and means for moving at least one of the fingers relative to the pivot to cause said fingers to grip a blank, a portion of one of said fingers being engageable with a blank in said die stage on movement of the finger to eject said blank following operation on the blank.

15. In means for presenting a blank to a die adapted to receive a blank fed thereto, said means comprising a pair of fingers having a common moving support, each of said fingers being movable relative to said support and having associated therewith independently actuated controlling means to cause movement of the finger independent of movement of the support and of the other finger.

16. In blank feeding means adapted to be employed with divided relatively movable dies and including a die having a recess in a face thereof adapted to receive a blank, the feeding means comprising a pair of fingers for presenting a blank to said die, the fingers being reciprocally 75 movable in a plane generally parallel to the plane

of the face of the die, and in a plane generally perpendicular to the plane of the face of the die, one of said finger elements pressing against and holding a blank in said die recess a portion of the time during movement in one direction of said fingers in the plane generally parallel to the plane of the face of the die.

17. In blank feeding means adapted to be employed with a die having a series of blank receiving stations each adapted to receive a blank, successive steps in a series of operations being performed at each successive station in the series of stations, the feeding means being adapted to present blanks to the first of said stations and to transfer blanks in each station to the successive stations in the series of stations, the blank feeding means comprising a moving support, a pair of fingers carried by said support, each of said fingers being movable relative to the support and having independently actuated controlling means 20 to effect movement of the finger independent of movement of the support and of the other finger to cause the fingers to grip and release a plurality of blanks, movement of the support effecting feeding of blanks to the first blank receiving station and the transfer of blanks from one blank receiving station to the next adjacent station in 25 said series of stations.

18. In a machine of the class described, a pair of dies having a plurality of complementary recesses therein, one of said dies being movable relative to the other of said dies and having an open and a closed position and, work feeding mechanism for transferring work blanks from one of said recesses to another while the dies are in 30 the open position, said means comprising a pair of fingers having an initial position, one of said fingers having a recess therein adapted to receive a blank to be transferred, said finger recess being substantially in alignment with a recess in the 35 dies when the finger is in the initial position, the fingers being movable from the initial position when the dies are open to bring the finger recess into alignment with another recess in the die whereby a blank may be transferred from one die 40 recess to another, the recessed finger being movable out of engagement with the work blank prior to the closing of the dies, the other of said fingers being adapted to yieldingly and slidably press 45 against the work blank and hold it in the second die recess intermediate the disengagement of the finger and the closing of the dies.

19. In a machine of the class described, a pair of dies having a plurality of complementary recesses therein, one of said dies being movable relative to the other of said dies and having an open and a closed position, work feeding mechanism for transferring work blanks from one of said recesses to another while the dies are in the open position, said means comprising a pair of fingers 50 having an initial position, one of said fingers having a recess therein adapted to receive a blank to be transferred, said finger recess being substantially in alignment with a recess in the dies when the finger is in the initial position, the finger being movable from the initial position when the dies are open to bring the finger recess into alignment with another recess in the die whereby a blank may be transferred from one die recess to 55 another, the recessed finger being movable out of engagement with the work blank prior to the closing of the dies, the other of said fingers being adapted to engage the work blank and hold it 60 in the second die recess intermediate the disengagement of the finger and the closing of the dies.

20. In blank feeding means adapted to be employed with divided relatively movable dies and including a die having a recess in a face thereof adapted to receive a blank, the feeding means comprising a pair of fingers for presenting a blank to said die, the fingers being reciprocally 70 movable in a plane generally parallel to the plane

gagement of the finger and the closing of the dies.

20. In a machine of the class described, feed mechanism comprising a pair of fingers, a movable support for said fingers, the fingers being movable by the support, one of the fingers being movable relative to the support, means for moving the support and independent means for moving the movable finger, the means for moving the support comprising a member pivotally mounted on a first axis spaced from the support and being pivotally connected to the support on a second axis spaced from the first axis, the means for moving the finger relative to the support comprising a member pivotally secured to the finger on a third axis and pivotally mounted on a fourth axis, the first and second axes, and the third and fourth axes being spaced apart substantially the same distance, and the first and fourth axes and the second and third axes being spaced apart substantially the same distance.
21. In a machine of the class described, feed

mechanism comprising a pair of fingers, a movable support for said fingers, the fingers being movable by the support, one of the fingers being movable relative to the support, means for moving the support and independent means for moving the movable finger, the means for moving the support comprising a member pivotally mounted on a first axis spaced from the support and being pivotally connected to the support on a second axis spaced from the first axis, the means for moving the finger relative to the support comprising a member pivotally secured to the finger on a third axis and pivotally connected on a fourth axis to an actuating member pivotally mounted on the first axis, the first and second axes, and the third and fourth axes being spaced apart substantially the same distance, and the first and fourth axes and the second and third axes being spaced apart substantially the same distance.
